UNITED STATES PATENT OFFICE

156,189

DESIGN FOR A PUSH TYPE DIAL
MICROMETER GAUGEWarren Ames, Newton, Mass., assignor to B. C.
Ames Co., Waltham, Mass., a corporation of
Massachusetts

Application February 16, 1949, Serial No. 894

Term of patent 14 years

(Cl. D52—1)

To all whom it may concern:

Be it known that I, Warren Ames, a citizen of the United States and a resident of Newton, county of Middlesex, Commonwealth of Massachusetts, have invented a new, original, and ornamental Design for a Push Type Dial Micrometer Gauge, of which the following is a specification, reference being had to the accompanying drawing, forming part thereof.

In the drawing—

Fig. 1 is a front view of a push type dial micrometer gauge, showing my new design;

Fig. 2 is a side elevation of the gauge, as viewed from the right of Fig. 1;

Fig. 3 is a rear view of the gauge according to Figs. 1 and 2; and

Fig. 4 is a bottom view of the gauge looking upward from below Fig. 1.

I claim:

The ornamental design for a push type dial micrometer gauge, substantially as shown.

WARREN AMES.
